ELECTRICAL CONDENSER

Application filed January 15, 1929. Serial No. 332,700.

This invention relates to improvements in the detailed construction of electric condensers of the variable type, such as used in radio receiving sets.

- 5 My improvements are illustrated in the accompanying drawing forming a part of the specification as applied to a group of condenser units which are arranged and carried by a unitary frame-work structure.
- 10 Where the condenser units are arranged in this manner, a single dial control serves to operate all of the condensers simultaneously.

Where all of the tuning condensers in a radio receiving set are operated by single 15 control devices it is very essential that each condenser be at the proper setting so as to bring each of the turned circuits to substantially the maximum point on the resonance curve for the frequency or wave length 20 of the station being tuned in on the receiving set.

It is therefore a big problem to get a plurality of condensers operated by a common control, set so as to produce the most 25 efficient and maximum result in the tuning of their respective circuits. I have found that where plain bearings are used for the rotor system, it is very hard to get these bearings in perfect alignment, especially 30 where three and four condensers are arranged in one gang, and that the manufacturing discrepancies set up mechanical stresses in the frame-work which displace one or more of the condenser units sufficient 35 ly to interfere with the proper tuning of the electrical circuits with which the condenser is associated. Keeping in mind the fact that the capacity of these air condensers is small, it will be readily appreciated that 40 a slight shifting of the relative position of a group of rotor plates with respect to the stator plates, will change the tuning characteristics of the condenser unit, and instead of all of the circuits being tuned to maximum 45 efficiency, one or more of them will be off the maximum point of the resonance curve.

It has been proposed to use certain electrical compensating devices in an endeavor 50 to overcome these inaccuracies in manufac-

ture, and some success has been accomplished along this line and one or more of these electrical compensating features are disclosed herein. However, from tests which I have made, I have found that far better results are obtained by the journalling construction disclosed. 55

It is therefore the principal object of my invention to overcome in the construction of a gang condenser, the mechanical difficulties hereinbefore referred to. While accomplishing the principal object of my invention, it is another object to provide a simple and relatively inexpensive means for accomplishing the main purpose of the invention which will be readily understood by reference to the annexed drawing, wherein: 60

Figure 1 is a plan view of a four-gang condenser with the rotor system fully in mesh with the stator system. 65

Figure 2 is a side elevation of Figure 1. 70

Figure 3 is an end view of the left-hand end of Figures 1 and 2.

Figure 4 is a section on the line 4—4 of Figure 2. 75

Figure 5 is a perspective view of a modified form of a combination compensating and friction applying device.

Figure 6 is an enlarged sectional view on the line 6—6 of Figure 3. 80

Figure 7 is an enlarged view on the lines 7—7 of Figure 1.

Figure 8 is a plan view of an individual separable bearing which may be used for the purposes hereinafter set forth. 85

Figure 9 is a vertical-sectional elevation of Figure 8.

Figure 10 is a view similar to Figure 8 taken from the reverse side, but showing a modified form of mounting the bearing member. 90

Figure 11 is a view similar to Figure 6, but of a modified form on a reduced scale from that of Figure 6.

Figure 12 is a plan view of a further modified form of holding plate. 95

Referring now to the details wherein like numbers refer to the corresponding parts in the various views, 1 is a frame-work having end support members 2 and 3, all pref- 100

erably of steel. The member 1 is preferably drawn out of metal of a suitable kind and somewhat trough-shaped. As shown in Figure 3, the end support members 2 and 3 are separate from the frame-work 1, but held thereto by projections 4 which extend through the members 2 and 3 and have their ends upset or spread as indicated by the lines 5. It is to be understood of course, 10 that the entire frame-work may be drawn out of one piece.

Both sides of the frame-work 1 are provided with openings 6, and positioned in each of these openings, is an insulator 7 of suitable material, the insulator 7 being fastened to the frame 1 in any suitable manner as by screws 8. The stator plates 9 of each 15 condenser, are fastened together by tie bars 10 which are fastened to the insulator 7 in 20 any suitable manner as by screws 11. Thus each stator group is carried on the frame 1 by means of these insulators 7.

The rotatable system includes a shaft 12 of suitable material, to which are attached 25 sleeves 13, these sleeves being held in position on the shaft 12 in any satisfactory manner as by screws 14. Each of the sleeves 13 carries a group of rotor plates 15, the outer 30 ends of which are held together in a permanent position by tie bars 16. As shown in Figure 1, only the outer rotor and stator plates of each unit are illustrated.

To eliminate the difficulties encountered 35 with plain bearings as set forth in the early part of this specification, I have devised the following construction:

As shown in Figure 1, I form on each of the end support plates 2 and 3, seats or races 17 for anti-friction devices such as balls 18. 40 To cooperate with the race 17, I provide the shaft 12 adjacent the dial end, with a groove 19 which is formed by a special tool. On the rear end support member 2, I attach 45 in any satisfactory manner, as by screws 20, a cover plate 21. The plate 21 covers the race 17 and at the same time serves to hold an engagement member 22 in position 50 against the balls 18. As it is seen in Figure 6, the member 22 has its outer edge formed into a rim 23 to lap over the outer periphery of the balls 18.

The extreme inner end of the shaft 12 is specially formed by a suitable tool into a race 24 which cooperates with the seat 17. 55 An adjusting device in the form of a screw 25 and lock nut 26 is used to hold the shaft 12 in proper longitudinal alignment, so that the balls 18 in the front and rear races are 60 in proper working position. This construction provides a support for the rotatable system in which friction is reduced to a minimum and there are no side or lateral strains on the rotatable system which tend 65 to displace the rotor plates from their true

planes which should be parallel to the planes of the stator plates.

Having eliminated or at least reduced to a minimum this mechanical difficulty, it will be apparent that the rotatable system will turn very freely, and due to the fact that in the design shown, the shaft 12 is somewhat off-center with respect to the center of the rotor plates, the rotatable system would not stay in adjusted tuning position over a considerable portion of the angular movement. Therefore, I have provided a special adjustable means for applying to the rotatable system the necessary amount of friction to cause the rotatable system to maintain its 70 75 adjusted tuned position.

This controllable friction is applied in the following manner:

The frame-work 1 is provided with one or more braces 27 which are positioned in 85 and carried by the frame 1 between each of the condenser units. These braces 27 may conform to the inner contour of the frame 1, or they may be cut out to some other desired shape. The brace 27 is provided 90 with a notch 29, in which is positioned a slotted end 30 of a friction applying member 31. The member 31 is bowed downward at 32 under the shaft 12, and has a forked end 33 which slips over the top of the brace 27, all as shown in Figure 4. An adjusting screw 33 and lock nut 34 is provided to adjust the amount of friction which the device 31 will apply to the shaft 12. By having one or more of the braces 27 provided with one of the friction applying devices 31, a very definite and positive amount 100 of friction can be applied to the rotatable system. By eliminating the mechanical friction in the bearings and then applying 105 a definite amount of friction by a controllable adjusting device, I have obtained a construction that may be used in the building of a single-unit condenser, but which is especially advantageous in the construction 110 of gang condensers and which is substantially free from the troubles that have existed in previous designs. It is to be understood that the shaft 12 may be operated in any desired manner as for example, by a 115 dial, drum, or other control means.

As shown in Figures 1 and 2, an electrical compensating condenser may be used. This comprises a single condenser plate 35 which is carried on the insulator 7 by the screws 11 and is thus electrically connected to each stator group of plates. The position of the auxiliary condenser plate 35 with respect to the frame 1, is adjusted by means of an adjusting screw 36 which passes through a 120 clearance hole in plate 35. An insulator 37 preferably of mica, is positioned around the screw 36 between the plate 35 and the frame 1, so as to prevent the plate from being 125 brought into contact with the frame 1, due 130

to any adjustment of the plate 35. The head of screw 36 is prevented from contacting with the plate 35 by an insulator 40 carried on the screw 36.

5 In place of the auxiliary condenser plate 35 as described, I may use a combination device such as shown in Figure 5, which comprises a U-shaped plate 39 attached to the member 31. The side pieces of the member 10 39 are adapted to pass downwardly over the sides of the braces 27 and may be spread to any desired degree to approach the rotor plates 15, whereby the capacity of the condenser units adjacent the parts 39 may be 15 slightly modified. It will be understood of course, that the auxiliary condenser 35 and compensating device 39 may both be used if desired.

In Figures 8, 9, and 10, I have shown an 20 individual separable bearing preferably of steel or metal sufficiently hard so as to present a smooth wearing surface of long life to the balls. In some cases it may be desirable to make the entire frame and the end 25 support members 2 and 3, of brass, aluminum, or die-cast material, and particularly when the latter is used, it is preferable to use a ball race of harder and better wearing material. Therefore, I have designed a 30 separable race 45 which may be attached to the support members 2 and 3 in any suitable manner as by screws passing through the holes 46. This arrangement is especially adapted for use if the end support members 35 2 and 3 are made of insulating material.

If the frame and end support members are made of die-casting, then I prefer to mould the race 45 directly to the frame structure, and to this end notches 48 are used for the 40 moulding material to flow into, to hold the bearings securely in position.

As shown in Figures 8, 9, and 10, 47 illustrates the seat for the balls, and 49 is the reverse side of these ball seats or races.

45 In Figure 11, I have shown a construction in which the shaft 12 passes all the way through the end bearing support 2, which construction may be desired for the purpose of attaching some other piece of apparatus 50 to the shaft 12. When this construction is used, the ball race 19 in the shaft 12, is positioned so that the balls engage the race 17 at the point 50 and the shaft 12 and balls are held in proper working position by 55 means of a plate 41 held to the end support member 2 by screws 20. In some cases it may be desired to make the special plate 42, as shown in Figure 12, somewhat more resilient than the plate 41 or the plate 21, shown in Figure 6, and to this end I have 60 cut away part of the metal, as indicated at 44, to make the plate 42 more resilient around the point where the plate engages the balls 18. As shown in Figure 12, the plate 65 42 is attached to the end support member

by means of screws passing through the screw holes 43.

Where the individual separable bearings 45 are used, the plate 42 may be used to hold the ball race 45 in position, as well as acting to hold the shaft in its proper working position.

70 From what has been said, it will be readily appreciated that certain of the details entering into the construction of my new and improved gang condenser, may be varied considerably without departing from the spirit of my invention or the scope of the appended claims; for example, a bearing support plate may be used between adjacent condenser units, for instance at the center of the condenser shown in Figure 1, and equipped with a ball race just the same as the end support member 3, and the shaft also provided with a ball race, thus providing an intermediate bearing.

75 Having thus described my invention, what I claim is:

1. An electrical condenser having a frame with end support members, at least one group of stator plates carried by said frame and a rotatable system including a shaft carried by said support members and carrying a group of rotor plates for cooperation with the group of stator plates, said end support members and the shaft having parts formed in each for and each carrying a plurality of anti-friction bearing devices, an engagement member for positioning said anti-friction bearing devices in one of said support members, a cover plate for holding said engagement member in working position, an adjusting device carried by said cover plate for holding said shaft in longitudinal alignment, and adjustable means for applying a desired amount of friction to said rotatable system.

100 2. An electrical condenser having a frame with end support members, a plurality of groups of stator plates carried by said frame and a rotatable system including a shaft carried by said support members and carrying a plurality of groups of rotor plates corresponding in number to and for cooperation with the groups of stator plates, said end support members and the shaft having parts formed in each for and carrying anti-friction bearing devices, a brace plate supported by the frame between at least two groups of stator plates, and an adjustable device carried on said brace plate and engaging a part of the rotatable system for applying a desired amount of friction to said rotatable system.

105 3. An electrical condenser having a frame with end support members, a plurality of groups of stator plates carried by said frame and a rotatable system including a shaft carried by said support members and

carrying a plurality of groups of rotor plates corresponding in number to and for cooperation with the groups of stator plates, said end support members and the shaft having parts formed in each for and carrying anti-friction bearing devices, a brace plate supported by the frame between adjacent groups of stator plates, a device mounted on each brace plate having a part extending into frictional engagement with said shaft, and means for adjusting each of said devices to secure the desired amount of friction on said shaft.

4. An electrical condenser having a frame with end support members, a plurality of groups of stator plates carried by said frame and a rotatable system including a shaft carried by said support members and carrying a plurality of groups of rotor plates corresponding in number to and for cooperation with the groups of stator plates, said end support members having seats formed therein for anti-friction bearing members, said shaft having an annular groove near its drive end to receive and hold said anti-friction bearing members in the seat in the front end support member, said shaft also having its inner end formed into a bearing race to cooperate with the seat in the rear end support plate to receive anti-friction bearing members, means on the rear end support member to hold the shaft and bearing members in working position, a brace plate between at least two groups of stator plates, and an adjustable device carried on said brace plate and engaging a part of the rotatable system for applying a desired amount of friction to said rotatable system.

5. An electrical condenser having a frame with end support members, a plurality of groups of stator plates carried by said frame and a rotatable system including a shaft carried by said support members and carrying a plurality of groups of rotor plates corresponding in number to and for cooperation with the groups of stator plates, said end support members having seats formed therein for anti-friction bearing members, said shaft having an annular groove near its drive end to receive and hold said anti-friction bearing members in the seat in the front end support member, said shaft also having its inner end formed into a bearing race and extending just through the wall of the bearing seat in the rear end support member whereby the shaft race can cooperate with the seat to receive anti-friction bearing members, a member engaging and holding the said bearing members in working position, a plate on the outer face of the rear end support member for covering said bearing seat, adjustable means carried by said plate for holding said engaging member and said shaft in operative

position, a brace for the frame positioned between adjacent groups of stator plates, a device mounted on at least one of said braces and having a part extending into frictional engagement with said shaft and means for adjusting said device to secure the desired amount of friction on said shaft.

6. An electrical condenser having a frame with end support members, a plurality of groups of stator plates carried by said frame and a rotatable system including a shaft carried by said support members and carrying a plurality of groups of rotor plates corresponding in number to and for cooperation with the groups of stator plates, said end support members having ball races formed therein, said shaft having ball races formed thereon for cooperation with the first-mentioned races, balls in said races, a cover plate for the ball race in the rear end support member, a member engaging the balls positioned in the last-mentioned race, adjustable means carried by said cover plate for holding said engaging member and said shaft in operative position, a brace for the frame positioned between adjacent groups of stator plates, a device mounted on at least one of said braces and having a part extending into frictional engagement with said shaft and means for adjusting said device to secure the desired amount of friction on said shaft.

7. An electrical condenser having a frame with end support members, a plurality of groups of stator plates carried by said frame, a shaft carrying groups of rotor plates for cooperation with said stator groups, said shaft being journaled on ball bearing carried between the shaft and said end support members, a brace between at least two groups of stator plates, a device mounted on said brace and having a part extending into frictional engagement with said shaft, and means for adjusting said device to secure the desired amount of friction on said shaft.

8. An electrical condenser having a frame with end support members, a plurality of groups of stator plates carried by said frame, a shaft carrying groups of rotor plates for cooperation with said stator groups, said shaft being supported by said end support members, means for reducing to a minimum frictional resistance between the shaft and said end support members, said means comprising anti-frictional bearings for the shaft, a brace between at least two groups of stator plates, a device mounted on said brace and having a part extending into frictional engagement with said shaft, and means for adjusting said device to secure the desired amount of friction on said shaft.

9. An electrical condenser having a frame with end support members, a plurality of

- groups of stator plates carried by said frame, a shaft carrying groups of rotor plates for cooperation with said stator groups, said shaft being supported by said 6 end support members, means for reducing to a minimum frictional resistance between the shaft and said end support members, said means comprising anti-frictional 10 bearings for the shaft, both ends of said bearings comprising race-ways carried by each of said end supports and cooperating race-ways formed directly in the shaft, the race-way at one end of said shaft being formed directly at the end thereof, an engagement 15 member for holding anti-friction members in the last mentioned race-way, and a cover plate for holding said engagement member in operative position, and adjustable means for applying a desired amount of friction 20 to said shaft.
10. An electrical condenser having a frame with end support members, anti-friction bearing races positioned on said end support members, a plurality of groups of 25 stator plates carried by said frame, a rotor system including a shaft carrying groups of rotor plates for cooperation with said stator groups, races formed in said shaft to cooperate with the first-mentioned races, 30 a plurality of anti-friction members positioned in each of said races, the race at one end of said shaft being formed directly at the end thereof, and means carried by the 35 cooperating end support for directly engaging said anti-friction members to hold the same and the shaft in longitudinal alignment, and adjustable means for applying a desired amount of friction independent of said shaft bearings to said rotor system.
40. 11. An electrical condenser having a frame with end support members, a plurality of groups of stator plates carried by said frame, a shaft carrying groups of rotor plates for cooperation with said stator 45 groups, said shaft being supported by said end support members, means for reducing to a minimum frictional resistance between the shaft and said end support members, said means comprising ball-bearing races 50 positioned on said end support members and cooperating races formed in said shaft with balls in said races; a cover plate for at least one of said pair of races to hold the shaft races and balls in working position, and 55 adjustable means for applying a desired amount of friction to said shaft.
12. An electrical condenser having a frame with end support members, a plurality of groups of stator plates carried by 60 said frame, a shaft carrying groups of rotor plates for cooperation with said stator groups, said shaft being supported by said end support members, means for reducing to a minimum frictional resistance between 65 the shaft and said end support members,
- said means comprising ball-bearing races positioned on said end support members and cooperating races formed in said shaft with balls in said races; means for holding the shaft races and balls in working position, a brace between at least two groups of 70 stator plates, a device mounted on said brace and having a part extending into frictional engagement with said shaft, and means for adjusting said device to secure the desired amount of friction on said shaft.
13. An electrical condenser having a frame with end support members, a plurality of groups of stator plates carried by said frame, a shaft carrying groups of rotor plates for cooperation with said stator groups, said shaft being supported by said end support members, means for reducing to a minimum frictional resistance between the shaft and said end support members, said means comprising ball-bearing races positioned on said end support members and cooperating races formed in said shaft with balls in said races; a resilient cover plate for at least one of said pair of races to hold the shaft races and balls in working position, a brace between adjacent groups of stator plates, a device mounted on each brace and having a part extending into frictional engagement with said shaft, and means for adjusting said devices to secure the desired amount of friction on said shaft.
14. An electrical condenser having a frame with end support members, a plurality of groups of stator plates carried by said frame, a shaft carrying groups of rotor plates for cooperation with said stator groups, said shaft being supported by said end support members, means for reducing to a minimum frictional resistance between the shaft and said end support members, said means comprising separable ball races adapted to be attached to each end support member, races formed in said shaft to cooperate with the first-mentioned races, balls positioned in said races, means for holding the shaft races and balls in working position, a brace between at least two groups of stator plates, a device mounted on said brace and having a part extending into frictional engagement with said shaft, and means for adjusting said device to secure the desired amount of friction on said shaft.
15. An electrical condenser having a frame with end support members, at least one group of stator plates carried by said frame, a rotatable system including a shaft carrying a group of rotor plates for cooperation with the stator plates, separable anti-friction races attached to each end support member, races formed in said shaft to cooperate with the first-mentioned races, anti-friction bearing members positioned in said races, means including an engagement member having its outer edge formed into a

rim to lap over the outer periphery of said anti-friction members, and an engagement member carried by the rear end support to hold said engagement member in position, thereby holding the shaft races and balls in working position, and adjustable means for applying to the rotatable system the desired amount of friction.

16. For an electrical condenser having a frame with end support members, a plurality of groups of stator plates carried by said frame, a shaft supported by said end support members and carrying groups of rotor plates for cooperation with said stator groups; means for specially supporting said shaft on said end support members, said special means consisting of, a race-way carried by each end support, and cooperating race-ways in the shaft with anti-friction members in said race-ways, the condenser being further characterized in having a pressure exerting device comprising a resilient sheet of metal having a central orifice through which the shaft projects, the metal of said sheet around the orifice acting as a partial ball race, said sheet having cut-out sections beyond the edge of the orifice whereby said sheet is rendered more resilient, so that substantially uniform pressure is applied to all of the anti-friction devices in the associated races, and adjustable means for applying a desired amount of friction to said shaft.

17. For an electrical condenser having; a frame with end support members, a plurality of groups of stator plates carried by said frame, a rotatable system comprising a shaft supported by said end support members and carrying groups of rotor plates for cooperation with said stator groups of plates; means for specially supporting said shaft on said end support members, said special means consisting of, a race-way carried by each end support, and cooperating race-ways in the shaft with anti-friction members in said race-ways, and adjustable means for applying to the rotatable system a desired amount of friction.

18. An electrical tuning device including a frame with end support members, a plurality of groups of stationary tuning members carried by said frame, a movable system comprising a shaft supported by said end support members and carrying groups of tuning elements for cooperation with said stationary tuning elements; means for specially supporting said shaft on said end support members, said special means consisting of, a race-way carried by each end support, and cooperating race-ways in the shaft with anti-friction members in said race-ways, and means for applying to the movable system a desired amount of friction.

19. A variable condenser including; end

support members, integral means mechanically connected to and between said members and having portions extending upwardly on opposite sides of the condenser, supporting tie bars, stator plates secured to said bars, and a single flat strip of insulation connected between each of said bars and said means, said strips of insulation being secured at a single end to said upwardly extending portions of said means, and at the other end to the supporting tie bars.

20. A variable condenser including; end support members, frame parts mechanically connected to and between said members and having portions extending upwardly on opposite sides of the condenser and having openings formed therein, supporting tie bars, stator plates secured to said bars, and a single flat strip of insulation connected between each of said bars and said frame parts, said strips of insulation being secured at a single end to said upwardly extending portions of the frame parts and extending into said openings and connected at the other end to said supporting tie bars exposed by said openings.

In testimony whereof, I affix my signature.
